UNITED STATES PATENT OFFICE.

GEORGE E. ALLEN, OF BRIDGEPORT, CONNECTICUT.

KEY-RETAINING DEVICE.

1,028,849.

Specification of Letters Patent. Patented June 11, 1912.

Application filed July 19, 1911. Serial No. 639,367.

To all whom it may concern:

Be it known that I, GEORGE E. ALLEN, a citizen of the United States, residing at Bridgeport, in the county of Fairfield and

5 State of Connecticut, have invented new and useful Improvements in Key-Retaining Devices, of which the following is a specification.

An object of the invention is to provide a 10 key retaining device for removably retaining a key in locked or unlocked position in a lock.

Among other features, my invention embodies a structure in which when the same is 15 connected to a key and to the shank of a door knob, the key will be retained within the lock and cannot be disengaged from the lock from the exterior side of the closure by the use of pliers or the like.

20 For the purpose mentioned, use is made of a loop formed of an integral piece of flexible wire and a retaining plate mounted to swing on one end of the loop, the said retaining plate being adapted to engage the 25 other end of the loop with the extreme outer ends of the loop being adapted to be passed through the eye of a key, inserted in a lock so that the key cannot be turned from the outer side of the lock or closure to which 30 the lock is secured.

Reference is to be had to the accompanying drawings, constituting a part of this specification, in which similar characters of reference denote corresponding parts in all 35 the views, and in which—

Figure 1 is a perspective view showing my device in applied position. Fig. 2 is an enlarged vertical sectional view showing the ends of the loop engaged by the retaining 40 plate. Fig. 3 is a horizontal sectional view taken on the line 3—3 in Fig. 2, looking in the direction of the arrow.

Referring more particularly to the views, I provide an integral piece of flexible wire 10 45 bent to form a loop, preferably U-shaped, the ends 11 of the said piece of wire having their extremities 12 bent outwardly for a purpose that will be hereinafter more fully disclosed.

50 Mounted to swing on one of the ends 11 is a retaining plate 13, the ends of the retaining plate being bent to form bearings 14, one of the bearings having one of the ends 11 passed therethrough so that the retaining plate will swing on the said end and the other bearing 14 being adapted to re-

movably receive the other end of the wire loop 10.

In the use of my device the wire 10 is passed over the shank of a door knob on the inner side of the door and the free end of the wire is then pressed into engagement with the open bearing 14 of the retaining plate 13, after which the extremities 12 are passed through the eye of a key 15 as shown in Fig. 1, thus retaining the key in engagement with the lock and preventing the same from being turned or pressed out of engagement with the lock from the outer side of the closure.

70 Although I am aware that various key fastening devices have been used heretofore, embodying the use of a U-shaped piece of wire, I aim to produce a more effective device by employing the retaining plate 13, 75 the said plate being arranged so that both ends of the wire 10 can be connected to the plate and retained in engagement therewith and when this has been accomplished the lower extremities of the wire 10 need only 80 be passed through the eye of the key to retain the same in engagement with the lock and when my device is used constantly in connection with the same key, the free end of the wire need not be disengaged from the 85 retaining plate each time that it is desired to retain the key in locked or unlocked position, but the free end of the wire can be permitted to remain in engagement with the plate 13 and the lower ends of the wire need 90 only be permitted to pass through the eye of the key to retain the same in engagement with the lock, while at the same time a slight upward movement of the wire 10 will disengage the same from the key without incurring the necessity of first disengaging one of 95 the ends of the wire from the retaining plate.

As a portable device, my key fastener is particularly useful in that when the free end 100 of the wire is engaged with the retaining plate, the device can be more easily carried in a pocket than if the free end of the wire were disengaged from the retaining plate so that the same would catch or tear the pocket 105 when it is desired to remove the device therefrom.

Having thus fully described the invention, what I claim as new, is:—

1. In a key fastening device, an integral 110 piece of flexible wire bent in a U-shaped form and having the extremities thereof bent

- outwardly therefrom and a retaining plate mounted to swing on one of the ends of the said wire and adapted for removable engagement with the free end of the said wire.
- 5 2. In a device of the class described, the combination of a looped piece of flexible wire and a retaining plate, the said retaining plate being mounted to swing on one of the ends of the said wire and adapted for removable engagement with the free end of the said wire.
- 10 3. In a key fastening device, a looped piece

of flexible wire and a retaining plate swingingly mounted thereon to retain the free ends of the said wire in spaced relation to 15 permit of inserting the free ends of the wire through the eye of the key.

In testimony whereof I affix my signature in presence of two witnesses.

GEORGE E. ALLEN.
